UNITED STATES PATENT OFFICE.

CHARLES HILTON, OF ALBANY, NEW YORK.

RAILROAD-SPlice FOR RAILROAD-TRACK BARS.

Specification of Letters Patent No. 23,026, dated February 22, 1859.

To all whom it may concern:

Be it known that I, CHARLES HILTON, of the city of Albany, State of New York, have invented a new Wrought-Iron Rail-Splice 5 for Railroad-Track Bars; and I declare the following specification, with the drawings hereto attached as part of the same, to be a full and complete description thereof.

Figure 1 represents a side or profile view 10 of my apparatus; Fig. 2 a cross section at x, y , Fig. 1; Fig. 3 a perspective view of the rails and splice as viewed from below; Fig. 4 is a plan, with one of the rails removed; Figs. 5 and 6 a plan of the gib and wedge. 15 Fig. 7 is a cross section like that of Fig. 2, showing another mode of shaping the splice.

Similar letters in the different figures denote the same parts of the apparatus.

It is well known that in the construction 20 of railroads for the purpose of preserving the level of the rails, and to keep the ends of the bars which head upon each other in line as to their upper edges and surfaces, so as to be prevented from settling down under 25 the pressure of the cars when passing over them; it is necessary to adopt some efficient security, other than the mere cross-ties on which the rails lie. This has been done sometimes by putting an iron plate or chair, 30 reaching some distance, under the ends of the rails, the plate or chair itself lying on a broad cross tie. The liability of the cross tie itself to settle by pressure of the loads passing on the rails rendered this a futile 35 contrivance. A better plan used has been to clamp the rails together by flat bars of iron, called fish-plates, lying opposite to each other in the thin part of the rails between the tread and the base and secured to 40 together by screw bolts or rivets. Even this plan has not proved to be reliable, for the rails have settled at their point of junction for want of sufficient depth in the fish-plates. My invention proposes to remedy these defects. 45

A, B, represents the two rails to be secured to each other; a, c the fish-plates, which extend in length about twelve inches, that is, six inches from the junction of the 50 rails each way. They are shaped so as to embrace the rail from the lower part of the

swell of the tread at e (see Figs. 2 and 3) along the side surface of the rail to f and then projects perpendicularly down below the bottom of the rail to d . In the lower 55 center portion of these fish-plates opposite the junction of the rails is cut a slot about three and a half inches long and of depth sufficient to admit of the insertion of a substantial gib g , and wedge h , which together 60 form a firm seat or rest for the ends of the rails. The fish-plates are also bolted or riveted at each end m , (or if necessary with additional bolts) so as to clamp them firmly 65 to the rails.

The gib and wedge, (see Figs. 4, 5, 6,) are provided with rows of holes appropriately arranged for the insertion of a check pin p to hold the wedge from sliding back 70 when driven up.

The apparatus or splice thus constructed can be placed between any two of the cross ties of the road.

Instead of forming the fish-plates as shown in Figs. 2 and 3 by carrying down 75 their sides from e along the rail, and from f perpendicularly below the rail, I can construct the splice as shown in Fig. 7, that is, by making it in its cross section a loop dropping below the rail and passing around and 80 over the tread embracing it closely and terminating at n —introducing the gib and wedge into a slot placed as described in the first mode of construction; putting the gib 85 above and wedge below. This plan will not require bolts through the plates and rail.

What I deem to be the peculiar advantages of the mode, above described of securing the ends of the rails are: I, that the extension of the fish plates below the rails 90 adds very much to their stiffness and to their resistance to depression; II, that the support afforded by the broad gib and wedge applied directly under the junction of the rails; and the facility with which through 95 them the stress and bearing of the fish plates can be adjusted and retained, makes the settlement of the ends of the bars almost an impossibility; III, that should from any cause the bars settle, they can be restored 100 to position with the least possible delay and trouble.

I do not claim the use of the plates nor | substantially in manner and for the pur-
the wedge broadly, but | poses set forth in the within specification.

I do claim—

Deep wrought iron fish plates secured to
5 the sides of the rails by bolts or keys, and
extending downward below the base of the
rail, in combination with the gib and wedge,

CHAS. HILTON.
